(57) **CLAIM**

The ornamental design for a timer, as shown and described.

DESCRIPTION

FIG. 1 is an elevated perspective view of a timer according to our new design; and,

FIG. 2 is a front view of the timer shown in FIG. 1. The portions of the timer depicted in broken lines form no part of the claimed design.

In FIGS. 1 and 2, the planar surface of the timer between the outer claimed circular edge and the inner claimed arcuate edge, with the exception of the claimed text, forms no part of the claimed design.

1 Claim, 2 Drawing Sheets
